M. N. FREEMAN

HEATING APPARATUS

Filed Dec. 16, 1926

UNITED STATES PATENT OFFICE.

MICHAEL N. FREEMAN, OF RACINE, WISCONSIN.

HEATING APPARATUS.

Application filed December 16, 1926. Serial No. 155,188.

This invention relates to heating apparatus.

In ordinary fireplaces, such, for example, as those built in a chimney and provided with a grate or with andirons, most of the heat passes up the chimney and is wasted, as it plays no part in heating the room.

Objects of this invention are to provide a novel heating apparatus in the nature of a fireplace which is so constructed that it heats the air by contact with heating surfaces and passes the heated air out into the room.

Further objects are to provide a novel form of fireplace in which the air heating means is hidden and does not detract from the pleasing appearance of an ordinary fireplace.

An embodiment of the invention is shown in the accompanying drawings in which:

Figure 1 is a vertical sectional view 20 through a chimney showing one form of the apparatus in place;

Figure 2 is a sectional view on the line 2—2 of Figure 1;

Figure 3 is a sectional view on the line 3—3 25 of Figure 1.

Referring to the drawings, it will be seen that a chimney 1 has been illustrated as built out into the room. This chimney is provided with an opening 2 adjacent its lower end 30 which constitutes a fireplace. The andirons or grate have been omitted from the drawings for the sake of clearness. This fireplace does not open back to the back wall of the chimney, but is spaced outwardly therefrom 35 by a metal back wall 3. This metal back wall has an upwardly and forwardly slanting portion and a rearwardly slanting portion 4. It is also provided with a removable plate 5 adjacent the part where the fire would contact, as this portion of the structure is subject to burning out and, consequently, is made removable so that it may be readily replaced. The removable portion 5, as shown in Figure 3, may be held in place by screws or pins 6.

The back plate 3 is provided throughout its extent with vertical ribs 7 on its rear face, and preferably with corrugated portions on its front face to increase the heating surface. Further, the sidewalls 8 are also spaced from the sides of the chimney, as shown most clearly in Figure 3. Obviously, therefore, when a fire is built in the fireplace, the back wall is highly heated and the air in the space behind such back wall and around the side walls is highly heated.

Means are provided for bringing the air into the space referred to above, and such means consists of openings 9 on opposite sides of the chimney, preferably covered by open work gratings 10 as shown in Fig. 3. It is also preferable, as shown in Figures 1 and 3, to line the chimney at this portion with a metal plate 11. This metal plate continues upwardly and, as shown in Figure 1, is provided with a forwardly slanting portion 12 and with a forwardly offset upper portion 11'. This offset portion is provided with a top plate 13. The upper portion of the back 3, particularly at its widened or rearwardly flared part 4, joins a transverse bottom plate 14. The plates 13 and 14 cooperate with a front metal plate 15 to form a heating box through which the air may be passed. The smoke and products of combustion of the fire are passed through pipes 16 which open 75 through the plates 14 and 13. Further, it is to be noted that baffles 17 are provided and carried by the back wall. These baffles direct the air forwardly into contact both with the heating back plate of the fireplace and 80 also with the heated tubes 16. Exits are provided for the air and preferably are arranged to that they open on opposite sides of the chimney adjacent the upper portion of the box-like air chamber. These exits are indicated in Figure 2 by the reference character 85 18. They are covered by gratings 19. When it is desired to use the device, a fire is built in the usual manner and no further thought on the part of the operator is required, other 90 than the adjustment of the usual damper 20, as shown in Figure 1. The products of combustion heat the tubes 16, and the back plate 3 is heated both from the products of combustion and from the radiant heat from the fire. 95 The air from the bottom portion of the room enters through the apertures 9 and passes behind the back plate where it becomes heated. This air passes upwardly and is thrown outwardly against the back plate by the lowest baffle 17. From thence, the air continues on its upward travel and is again thrown forwardly by the upper baffle plate 17, and consequently contacts with the highly heated tubes 16 and absorbs further heat. The heated air rises and passes laterally outwardly 105 through the apertures 18 and into the room.

It will be seen, therefore, that all of the benefits of an open fire are secured and, in addition to this, the efficiency of a stove is 110

also secured, as the air is heated by direct contact with heating surfaces formed in conjunction with the fireplace, although these surfaces, as stated, are not exposed to view and, consequently, do not detract from the pleasing appearance of an open fire.

It is to be noted further that a rapid circulation of air is secured by this construction and consequently, the room may be quickly heated by this open fire.

It is to be noted that the device consists essentially of a unit which may be placed in an ordinary straight chimney with the utmost ease and which adapts the open fireplace to the heating by direct contact of large volumes of air without in any way detracting from the appearance of the open fireplace.

Although the invention has been described in considerable detail, such description is intended as illustrative rather than limiting as the invention may be variously embodied and as the scope of such invention is to be determined as claimed.

I claim:

In a heating apparatus, the combination of a chimney, a fireplace adjacent the lower

end of the chimney, said fireplace being spaced from and surrounded on three sides by the chimney allowing a free circulation of air around the three sides of the fireplace, a transverse plate adjoining the upper end of the fireplace with the front wall of the chimney, a plurality of tubes opening through said plate, an upper plate through which said tubes open, a casing joining said upper plate with said transverse plate and surrounding said tubes, said casing being spaced from the chimney walls on three sides and joining the rear wall of the chimney to form an air heating chamber, openings in the sides of said casing adjacent its upper end through which heated air may pass, said chimney having openings in its side walls adjacent its lower end through which the cool air may pass behind the walls of said fireplace, and a baffle plate positioned within and secured to the rear wall of the chimney to direct the cool air into contact with the casing of the fireplace.

In testimony that I claim the foregoing I have hereunto set my hand at Racine, in the county of Racine and State of Wisconsin.

MICHAEL N. FREEMAN.
